United States Patent Office

Des. 184,063
Patented Dec. 9, 1958

184,063

COMPUTER CONSOLE UNIT

David G. Moore, Johnson City, and Walter Furlani,
Endicott, N. Y., assignors to International Business
Machines Corporation, New York, N. Y., a corporation
of New York

Application December 26, 1957, Serial No. 49,035

Term of patent 14 years

(Cl. D26—5)

The single figure is a front perspective view of a computer console unit, embodying our design.

The right side of the unit is the same as the left side and the rear of the unit is plain.

We claim:

The ornamental design for a computer console unit, as shown and described.
